CLAIM

The ornamental design for a head for a walking and sock assisting device as shown and described.

DESCRIPTION

FIG. 1 is a top, front, left-side perspective view in accordance with a head for a walking and sock assisting device; FIG. 2 is a front elevation view of the design of FIG. 1; FIG. 3 is a rear elevation view of the design of FIG. 1; FIG. 4 is a right-side elevation view of the design of FIG. 1; FIG. 5 is a left-side elevation view of the design of FIG. 1; FIG. 6 is a top, plan view of the design of FIG. 1; FIG. 7 is a bottom view of the design of FIG. 1; and, FIG. 8 is an environmental perspective view of the design of FIG. 1.

The broken lines in the figures show portions of the head for a walking and sock assisting device that form no part of the claimed design.

1 Claim, 6 Drawing Sheets
